UNITED STATES PATENT OFFICE.

CHARLES BALDWIN SAWYER, OF CLEVELAND, OHIO, ASSIGNOR TO THE BRUSH LABORATORIES COMPANY, OF CLEVELAND, OHIO.

THERMOSTATIC CONTROLLING MECHANISM.

Application filed November 17, 1922. Serial No. 601,652.

This invention relates to improvements in thermostatic controlling mechanism and more particularly to such as depend for their operation upon the expansion or contraction 5 of a fluid due to temperature changes,—one object of the invention being to so construct thermostatic controlling devices, that the same shall be operable to maintain constant, the temperature of a chamber, and so that adjustment 10 may be effected to maintain constant, any one of a number of different temperatures, and to provide simple and efficient electric circuit make-and-break mechanism forming part of the controlling mechanism and cooperable with the thermostatic elements thereof to insure accurate control of 15 a temperature regulating device for the chamber, the temperature of which is to be maintained constant.

20 A further object is to provide simple and efficient temperature controlling devices employing fluid as the actuator, with which minute adjustments may be effected for any predetermined degree of temperature, by 25 changing the capacity of the system in which the actuating fluid is contained, and to so construct and arrange the mechanism that the same shall be useful in refrigerating systems.

30 With these and other objects in view, the invention consists in certain novel features of construction and combinations of parts as hereinafter set forth and pointed out in the claims.

35 In the accompanying drawings:

Figure 1 is a view partly in elevation and partly in section showing an embodiment of my invention;

Figure 2 is an end view, and

40 Figure 3 is a plan view.

In the embodiment of my invention illustrated in the drawings, I have shown a base block or plate 1, to the under side of which, the upper edges of metal bellows 2 and 3 are 45 permanently secured by welding, brazing, soldering or in any other manner to effect an air tight connection. The bellows 3 is appreciably smaller in diameter than the bellows 2 and is located within the latter 50 so that a chamber 4 is formed to contain an expansible liquid,—such as acetone, for example. A cylinder 5 of thin metal and open at its lower end is disposed between

the two bellows to prevent possible interlocking of the folds of said bellows. The base block or plate 1 is provided with a 55 duct 6 which communicates at one end with the chamber 4 between the bellows and with the other end of said duct, one end of a tube 7 is connected,—the other end of said tube 60 having a bulb 8 (preferably of metal) connected thereto and intended to be located in a chamber, the temperature of which is to be regulated. The bulb 8, tube 7 and duct 6 and chamber 4 are completely filled with expansible liquid so that no vapor space will be left in the system comprising these elements, and such liquid may be introduced through 65 a suitable opening in the bulb and such opening then permanently closed.

70 The block or plate 1 and the parts carried thereby may be supported on a yoke or frame 9. The bottom of the bellows 2 is provided with a depending rod or tube 10 which is internally threaded to receive an adjusting screw 11,—the latter being loosely mounted in a hole in the cross bar 9^a of the frame 9 and capable of longitudinal movement through said hole. At its lower end, the screw may be provided with a manually 75 operable knob 12 to facilitate operation of the same to adjust the capacity of the bellows 2. A spring 12^a is disposed between the bottom of the bellows 2 and the cross bar of the yoke or frame 9 and serves to 80 maintain said bellows in its normal working position and adapted to yield during the operation of the system only when an abnormal pressure occurs therein,—said spring 85 thus acting as a safety device.

90 In the embodiment of my invention shown in the drawings, a lever 13 is pivotally supported between its ends by a bracket 14 secured to but insulated from the block or plate 1 and this lever has pivoted thereto between its pivotal support and its rear end, a lug 15, the latter being made to engage the insulated upper end of a rod 16 which passes downwardly through an opening in the block or plate 1 and is made rigid with the bottom 95 of the inner bellows 3.

An insulating block 17 secured to the base plate 1, carries a binding post 18, to which is attached a flat spring 19 and the latter carries a contact point 20,—upward motion 100 of the spring 19 being limited by a stop 21.

The movable contact 22 of the make-and-break mechanism is carried by the free end portion of a steel spring arm 23 secured to and in effect constituting a continuation of the forward arm of the lever 13, and between the rear arm of said lever and a bracket 13^a supported upon but insulated from the plate 1, a coiled spring 13^b is interposed and serves to maintain the lever 13 in operative relation to the rod 16.

The contacts 20 and 22 may be connected in any suitable manner in circuit with a temperature regulating device, but as these details form no part of my present invention, they need not be shown and described herein. It may be explained however that one circuit wire will be connected with the binding post 18 and the other with a binding post 24 in mounted on the base 25 of the bracket 13^a.

A magnet 26 (preferably of the horse-shoe type) may be supported on the end of the base plate 1, in such position that its poles will be in proximity to the steel spring 23,— the latter acting, in effect, as an armature for said magnet, so that when the contact 22 approaches the contact 20, said spring will come within the lines of force of the magnet and the contacts caused to close quickly, the force of said magnet being sufficient to force the spring 19 down against the insulating block 17, which arrests the travel of the spring 23 and prevents it from striking the poles of the magnet 26.

When the lever 13 is actuated in one direction by movement of the head of bellows 3 and the spring 23 has been flexed sufficiently, said spring will leave the magnet, but the spring 19 will cause contact point 20 to follow-up and remain in contact with contact point 22 until restrained by stop 21. Thus at the time when the force exerted by the flexed spring 23 is almost equal to the restraining force of the magnet 26, the spring 19 holds the contact points firmly together and prevents fluttering and consequent destructive sparking which might otherwise occur at this time. Furthermore, the spring 19 holds the contact points together until the spring 23 has definitely left the magnet 26 and is moving rapidly, so that the circuit is broken suddenly and with a minimum sparking when the stop 21 restrains the motion of the contact point 20. Should the contact points stick together by reason of an unduly large electric current through them, or for any other cause, the pivoted member 13 in conjunction with the spring member 23 will constitute a toggle system so that a large force will be developed tending to slide the contact points 22—20, one over the other in addition to the normal separating force, and in this way break them apart and effect their separation. In normal operation this

toggle joint action is likewise present to some extent, and causes a lateral or sliding motion of the contact points with respect to each other, both on opening and closing, which tends to keep the contact surfaces bright and in good electrical condition. The general arrangement of the contact members and their actuating mechanism forms the subject matter of my copending application Serial No. 601,653, filed November 18th, 1922 and entitled "Thermostat control mechanism."

With the construction and arrangement of parts hereinbefore described, the circuit will be opened upon a fall of temperature in the chamber, the temperature of which is to be kept constant, and closed when the temperature in said chamber rises, and hence my improvements are eminently adaptable for use with systems of refrigeration. If the machine be designed for very low temperatures, the liquid system will be protected against bursting due to high temperatures during shipment or before installation, by the relieving action of the spring 12^a, said spring, while normally retaining the bellows 2 against movement, permitting said bellows 2 to expand in the event of the development of dangerous pressures by expansion of the liquid contained in the thermostatic system.

With the use of my improvements, I am enabled to maintain a temperature in the chamber in which the bulb 8 is located, which will be as constant as may be desired, closeness of regulation depending on the volume of the liquid system.

Having fully described my invention, what I claim as new and desire to secure by Letters Patent, is:—

1. In mechanism of the character described, the combination of thermostatic means including two extensible cup-shaped bellows having their open ends connected to a closing member and having relatively movable closed ends disposed one within the other forming a fluid chamber between them, and electric circuit opening and closing means connected with the inner bellows.

2. In mechanism of the character described, the combination of thermostatic means including two extensible cup-shaped bellows, a plate to which the open ends of both bellows are connected, one within the other forming a fluid chamber between them, the closed ends of said bellows being relatively movable, electric circuit opening and closing means connected with the inner bellows, and means for adjusting the volume of the outer bellows.

3. In mechanism of the character described, the combination of thermostatic means including two cup-shaped bellows, one within the other forming a fluid chamber between them, a plate to which the open ends

of both of said bellows are connected, means interposed between the two bellows preventing interlocking of their folds, and means for utilizing movements of the inner bellows.

4. In mechanism of the character described, the combination of thermostatic means including two cup-shaped bellows, one within the other forming a fluid chamber between them, means for adjusting the volumetric capacity of outer bellows without changing the capacity of the chamber, and mechanism actuated by movements of the inner bellows.

5. In mechanism of the character described, the combination of thermostatic means including two cup-shaped bellows, one within the other forming a fluid chamber between them, and connected to the same side of a closing plate, a spring retaining the outer bellows in position during normal operation of the mechanism but adapted to yield upon development of abnormal pressure, and electrical make-and-break mechanism operatively connected with the inner bellows.

6. In mechanism of the character described, the combination of a base plate, two bellows one within the other and having fixed connection with said plate and forming a fluid chamber between them, a duct in the base plate in free communication with said chamber, electrical controlling means operatively connected with one end of the inner bellows, a bulb for location in a chamber the temperature of which is to be maintained substantially constant, a tube connecting said bulb with the duct in said base plate, and expansible liquid completely filling said bulb, tube, duct and the chamber between said bellows.

7. In mechanism of the character described, the combination of two bellows, one of said bellows enclosing the other and spaced therefrom, a tube communicating with the chamber formed by said bellows, a bulb communicating with said tube, said chamber, tube and bulb being permanently closed and filled with expansible liquid, an electric circuit closer and breaker, and connections between said circuit closer and breaker and the inner of said bellows.

8. A thermostat cartridge comprising a support, an extensible cup-shaped bellows having its open end secured to said support, a cup-shaped container encasing the first named bellows and secured to the same side of said support to thereby provide a closed chamber between the container and the bellows, means adapted to adjust the volume of the cup-shaped container without changing its liquid content to thereby control the relative position of said bellows with respect to said support, means adapted to maintain said bellows in adjusted position

for normal operation of the device, actuated mechanism having limited range of movement controlled by the operation of said bellows, and means permitting an abnormal movement of the bellows resulting from abnormal increase in the volumetric capacity of said cartridge under predetermined abnormal conditions without affecting a corresponding movement of the extensible portion of the bellows.

9. A thermostat unit comprising a base, a thermostat cartridge carried by the base embodying an extensible bellows of cup-shape having its open end secured to the support, mechanism actuated by the movement of said extensible bellows over a limited range of movement, a cup-shaped container completely enclosing said extensible bellows and having its open end secured to the support for said extensible bellows and having its side walls spaced from the side walls of said extensible bellows, said extensible bellows being received within said cup-shaped container and adapted to define therewith and with one side of said support, a closed chamber, liquid adapted to completely fill said chamber, and normally inoperative releasing mechanism adapted to permit abnormal expansion of the liquid contained within said chamber independent of the restricted movement of the mechanism actuated by said cartridge.

10. A thermostat unit comprising a base, a thermostat cartridge carried by the base embodying an extensible bellows of cup-shape having its open end secured to the support, mechanism actuated by the movement of said extensible bellows over a limited range of movement, a cup-shaped container completely enclosing said extensible bellows and having its open end secured to the support for said extensible bellows and having its side walls spaced from the side walls of said extensible bellows, said extensible bellows being received within said cup-shaped container and adapted to define therewith, a closed chamber, liquid adapted to completely fill said chamber and normally inoperative releasing mechanism adapted to permit abnormal expansion of the fluid contained within the chamber without causing a corresponding abnormal operation of the device controlled thereby.

11. A thermostat cartridge comprising a support, an extensible cup-shaped bellows having its open end secured to a support, a cup-shaped container encasing the bellows and secured to the same side of said support to thereby provide a closed chamber between the container and the bellows, a plunger actuated by the bellows passing through a closely fitting guide aperture in said support, means adapted to adjust the volume of said container without changing its liquid content to thereby provide a permanently

sealed thermostat cartridge having an enclosed bellows and plunger that is adjustable relative to said support.

12. A thermostatically operated circuit making and breaking mechanism comprising in combination a support, switching means adapted to make and break an electric circuit, an extensible thermostatic cartridge mounted on the support embodying a liquid filled chamber having an extensible portion, means connecting the extensible portion with the switching means, and means adapted to positively adjust the position of the extensible portion of said chamber relative to the support without changing the volume of liquid in the system.

13. A thermostatically operated circuit making and breaking mechanism comprising in combination a support, switching means adapted to make and break an electric circuit, mounted on the support, a thermostatic cartridge adapted to actuate said switching means permanently secured to the support and embodying a bellows portion, a cup-shaped member having its walls spaced from the bellows and forming in cooperation with a cover an enclosed chamber, thermally responsive liquid completely filling the chamber, means connecting the bellows with said switching means, and means adapted to positively adjust the position of the bellows relative to the support without changing the volume of liquid in the thermostatic cartridge.

14. A thermostatically operated circuit making and breaking mechanism comprising in combination a support, switching means adapted to make and break an electric circuit, a thermostat cartridge secured to the support and having portions adjustable with respect to said actuating means, said cartridge comprising a bellows and a cup-shaped member spaced from said bellows and forming in cooperation with a cover a sealed liquid-tight chamber, thermostatic liquid completely filling said chamber, means operatively connecting the bellows and the switching means, and means adapted to adjust the operative relation between the bellows and the switching means for changing the temperature at which the switching means is actuated by said mechanism without changing the volume of liquid in said chamber.

15. A thermostatically operated circuit making and breaking mechanism comprising a support, switching means adapted to

make and break an electric circuit, a thermostat cartridge mounted on the support and adapted to actuate said switching means, said cartridge comprising an extensible bellows, a cup-shaped container spaced from said bellows and forming in cooperation therewith an enclosed chamber adapted to be completely filled with a thermostatic liquid, a thermostatic liquid completely filling said chamber, a remotely positioned inextensible chamber of materially greater capacity than said enclosed chamber completely filled with thermostatic liquid, a connecting passageway extending from said container to said remotely positioned chamber completely filled with liquid, and means adapted to adjust the operative relation between the switch actuating means and the bellows without changing the liquid content of said chambers and said passageway.

16. A thermostatically operated circuit making and breaking mechanism comprising a support, switching means mounted on said support and adapted to make and break an electric circuit, a thermostatic cartridge secured to the support, said cartridge having a portion adapted to engage and actuate said switching means, said cartridge also comprising a yielding bellows, a sealed enclosure partially formed by said bellows, liquid completely filling the enclosure, and means acting independent of a change in the volumetric content of the enclosure adapted to change the relation of the bellows to the support for adjusting the relation of said bellows and said switching means to thereby regulate the temperature at which said switching means is actuated.

17. A thermostat electric circuit controller comprising a support, switching means adapted to control an electric circuit, an extensible container adapted to actuate said switching means, a second container of materially greater volume in open communication with the first named container, both of said containers and the communicating passage being completely filled with thermally responsive liquid, and means adapted to regulate the volume of said first container without changing the volume of liquid in the system in order to change the temperature at which said switching means is actuated.

In testimony whereof, I have signed this specification.

CHARLES BALDWIN SAWYER.
